[57] CLAIM

The ornamental design for a wall calendar, as shown and described.

DESCRIPTION

FIG. 1 is an isometric view showing a wall calendar embodying my new design;

FIG. 2 is a view in rear elevation;

FIG. 3 is a view in side elevation taken from one end of FIG. 1;

FIG. 4 is a view in side elevation taken from the other end of FIG. 1;

FIG. 5 is a top plan view;

FIG. 6 is a bottom plan view;

FIG. 7 is a view in section taken along line 7—7 of FIG. 1; and

FIG. 8 is a view in section taken along line 8—8 of FIG. 1.

The broken lines indicating the conventional indicia are shown for illustrative purposes only.
